UNITED STATES PATENT OFFICE.

HARRY HUNTER, OF INDIANAPOLIS, INDIANA, ASSIGNOR TO THE HUNTER DRY KILN COMPANY, OF INDIANAPOLIS, INDIANA, A CORPORATION OF INDIANA.

DRY-KILN.

1,254,142.

Specification of Letters Patent. Patented Jan. 22, 1918.

Application filed February 12, 1917. Serial No. 148,024.

To all whom it may concern:

Be it known that I, HARRY HUNTER, a citizen of the United States, residing at Indianapolis, in the county of Marion and 5 State of Indiana, have invented a new and useful Dry-Kiln, of which the following is a specification.

The object of my invention is to produce a dry kiln for producing drying at a 10 rapid rate, without injury to the articles being dried. My present invention is a further development and improvement of what is shown in my Patent No. 1,067,921, but omits some of the features shown in the latter, and involves certain new features by 15 which the rate of drying may be materially increased, greater flexibility of control obtained, and the parts rendered more easily accessible.

20 The accompanying drawings illustrate my invention. Figure 1 is a vertical longitudinal section through a dry kiln constructed in accordance with my invention, with some parts broken away, and with some of the 25 doors closed and some open; Fig. 2 is a section on the line 2—2 of Fig. 1; and Fig. 3 is a fragmentary detail of the damper controlling the air inlets on each side.

A substantially closed room or compartment is formed by end walls 5 and 6, side walls 7 and 8, a ceiling 9, and a floor 10, all 30 of which are preferably properly heat insulated; at least one of the end walls being provided with a door 11.

35 On each side of this compartment and parallel to the side wall 7 or 8 is a series of doors 12, which are hinged at their upper edges to a beam 13 extending down from the ceiling 9 so that they can be swung either 40 to vertical position, as shown in full lines in Fig. 2, or to horizontal position just below the ceiling 9, as indicated in dotted lines at the left of Fig. 2 and as shown at the right hand end of Fig. 1. When the doors 12 are 45 swung to horizontal position their free ends are supported from the ceiling 9 by suitable hooks 14. Each set of doors 12, when lowered, form with the associated beam 13 a partition parallel to but spaced from the 50 adjacent side wall 7 or 8, which partition extends from the ceiling 9 down fairly close to the floor 10. Directly below the lower edges of each series of doors 12 but spaced therefrom is an open water vessel 15 extending 55 the full length of the compartment and

supplied in any suitable way with water which is heated by steam pipes 16 immersed in the water in such vessel, the water vessel 15 being supported on a beam 17 resting on the floor 10.

60 Between each series of doors 12 and the adjacent side wall 7 or 8 is a second series of doors 18, which are hinged at their lower edges to a beam 19 extending up from the floor 10 slightly beyond the upper edge of 65 the water vessel 15 so that they can either be swung to vertical position as shown in full lines in Fig. 2 or swung downward to approximately horizontal position overlying the water vessel 15. The normal upper edges 70 of the doors 18 are provided with blocks 20 which serve to support the outer edges of these doors when they are lowered and to space the doors 18 from the doors 12 when both are in vertical position. Corresponding 75 blocks 20' may be provided on the lower ends of the doors 12. The doors 18, when raised, form with the beam 19 a partition parallel to but spaced from both the adjacent side wall 7 or 8 and the partition formed 80 by the doors 12, which partition formed by the doors 18 projects from the floor up fairly close to the ceiling 9.

85 The doors 18 are spaced from both the adjacent side wall 7 or 8 and from the doors 12, but are considerably closer to the doors 12 than to the side wall. In the space between the doors 18 and the side walls 7 or 8 is located a group of steam pipes 21, which 90 are supplied with steam in any suitable manner. Air inlet pipes 22 project in through the lower edge of each side wall 7 and 8 and are turned upward at their inner ends so as to discharge upwardly on to the steam pipes 21. The inlet ends of these air inlet pipes 22 95 are provided with dampers 23, which may be operated in the usual manner of dampers, as is clear from Fig. 3, to vary or shut off the supply of air through such pipes, the two dampers 23 for the two sets of 100 air inlet pipes on the two sides of the compartment being separately controlled. The upper end of the space between the doors 18 and the side walls 7 or 8 is connected over the upper edges of the doors 18 with 105 the space between such doors and the doors 12, and preferably a curved baffle surface 24 is provided over the upper edges of the doors 18 at the top of the space between the side walls 7 or 8 and the doors 12 for turn- 110

ing the ascending air from around the steam pipes 21 downward into the space between the doors 18 and the doors 12.

Air outlet pipes 25 project through the beams 17 and 19 on each side from the lower part of the central drying chambers, and these pipes 25 turn upward and are carried past the steam pipes 21 into a drum 26, located on each side in the upper part 10 of the space between the side wall 7 or 8 and the doors 12. From each of these two drums 26, a pipe 27 extends upward either to the atmosphere or to the inlet side of a suitably driven blower 28, common to the 15 pipes 27, or branches to both as shown, the blower 28 discharging at any convenient point to the atmosphere. A butterfly valve 29 controls the connection from each drum 26 direct to the atmosphere, and a similar valve 20 30 the connection from each drum to the blower 28.

If desired, there may also be provided return pipes 31 which are interspersed with the outlet pipes 25 and like the latter project through the beams 17 and 19 from the lower part of the central drying chamber and turn upward into the spaces between the respective side walls 7 and 8 and the doors 12. The pipes 31, however, discharge 35 upward into such space onto the steam pipes 21, as do the air inlet pipes 22. The inlet ends of the pipes 31 are provided with dampers 32, similar to the dampers 23, the dampers 32 for the two sets of return pipes 31 on the two sides of the compartment being controlled separately from each other and from the dampers 23.

In operation, the heat of each set of steam pipes 21 causes the air to rise in the feeding 40 space between the doors 18 and the side wall 7 or 8, drawing in air from the atmosphere through the air inlet pipes 22 if the dampers 23 are open and from the main drying chamber through the return pipes 31 if the dampers 32 are open. This air is heated or re-heated as it passes upward over the steam pipes 21, and when it reaches the top of the feeding space containing such pipes passes over the upper edges of the door 18 and 45 downward through the feeding space between the doors 12 and the doors 18. When it reaches the bottom of this latter space, it passes under the lower edges of the doors 12, and into the central drying compartment 50 between the two sets of doors 12, in which are placed the articles to be dried. As the heated air passes under the lower edges of the doors 12, it strikes the heated water in the vessel 15, and becomes humidified thereby 55 to a definite extent, depending upon the temperatures of the air and water, which can be varied if desired. The humidification of this air materially assists in the drying, and enables it to take place more quickly and at 60 a higher temperature than if the air were

not humidified. The air circulates through the drying chamber, to produce the desired drying, and then passes out at both sides through the return pipes 31, for reheating as set forth, or through the air outlet pipes 25, which carry it to the drums 26, whence it passes by the pipes 27 to the atmosphere, through the blower 28 or not according to the setting of the valves 24 and 30. The blower 28 may be used to produce a forced 75 circulation when that is desired; though for most drying operations the circulation is rapid enough without operating such blower, for a natural circulation occurs by reason of the heating effect of the steam 80 pipes 21 not only on the incoming air from the inlet pipes 22 and the return air from the pipes 31 but also on the outgoing air in the pipes 26.

The circulation which has been described 85 is duplicated at both sides of the compartment, if the dampers 23 and 32 and the valves 29 or 30 are all open. However, the circulation may be modified by closing either damper 23, either or both dampers 32, either 90 or both valves 29, either or both valves 30, or some combination of these. Thus if one damper 23 and both dampers 32 are closed while the other damper 23 and both valves 29 or 30 remain open, the air enters at one 95 side, circulates through the drying chamber, and leaves through the pipes 25 at both sides, passing to the atmosphere either direct or through the blower 28 according to whether it is the valves 29 or the valves 30 which 100 are open; there is no re-heating of the air in this arrangement. Correspondingly, if one valve 29, both valves 30, and both dampers 32 are closed, while the other valve 29 and both dampers 23 remain open, the air 105 enters at one side, circulates through the drying chamber, and leaves through the pipes 25 at one side only, passing to the atmosphere without going to the blower 28; there is also no re-heating of the air in this 110 arrangement. In the arrangement just described, a forced circulation may be obtained by the blower 28 by closing the open valve 29 and opening the valve 30 in the same pipe 27. If one damper 23, both dampers 32, 115 one valve 29, and both valves 30 are closed, while the other damper 23 and the other valve 29 remains open, all the air enters at one side and leaves at one side, the side of entrance and the side of leaving being either 120 the same side or opposite sides according to which of the valves 23 and which of the valves 29 are open. Here also there is no reheating, and as before a forced circulation instead of a natural circulation may be 125 obtained before closing the valve 29 and opening the corresponding valve 30. By opening one or both dampers 32, some of the air drawn from the central chamber is carried again over the pipes 25 and re- 130

heated and then carried back to the drying chamber. This may be done on either or both sides, with fresh air from the atmosphere being drawn in on the same side or sides or not. For instance, by opening the damper 23 on one side only, and the damper 32 on the other side only, fresh air is drawn in on the first side, and air from the central drying chamber is drawn out at the other side near the bottom and re-heated and sent back into the drying chamber. Other modifications of these arrangements may be used by different arrangements of the valves and dampers.

15. By using pipes 21 for heating air entering at both sides, it is possible to obtain a very considerably higher drying temperature; which may be still further raised by re-heating the air drawn from the bottom of 20 the drying chamber through the return pipes 31. It is possible to use this high drying temperature by reason of the humidifying of the air by the water in the vessels 17: and certain effects can be obtained by this 25 higher temperature which are not possible at lower temperatures. The dampers 23 and 32 and the valves 29 and 30 provide an absolute control of the amount and direction of the circulation. The hinged mounting of 30 the doors 12 and 18 renders the steam pipes 21 accessible for cleaning and repairing. In some instances, one set of air inlet pipes with a set of steam coils, or one set of air outlet pipes, or one or both sets of return 35 pipes, or either the direct discharge to the atmosphere or the discharge through the blower for forced circulation, or several of these, may be omitted; but in order to make possible a higher drying temperature I prefer to have both sets of air inlet pipes with their steam pipes and water pans even 40 though other features be omitted.

I claim as my invention:

1. A dry kiln, consisting of a main or outer compartment having a ceiling and walls, a partition projecting downward into said compartment near one wall, a second partition projecting upward between said first partition and the adjacent wall, said 50 partition being respectively spaced from the floor and the ceiling of said compartment and the two partitions being spaced from each other and from said wall, heating means located in the space between said second partition and the adjacent wall, said space being provided with an air inlet opening at the bottom and said compartment being provided with an air outlet opening, each of said partitions consisting of a plurality of doors, the doors of the partitions nearer the adjacent wall being hinged at the bottom and those of the other partition being hinged at the top.
2. A dry kiln, consisting of a main or outer compartment having a ceiling and

walls, a partition projecting downward into said compartment near one wall, a second partition projecting upward between said first partition and the adjacent wall, said partitions being respectively spaced from 70 the floor and the ceiling of said compartment and the two partitions being spaced from each other and from said wall, heating means located in the space between said second partition and the adjacent wall, said 75 space being provided with an air inlet opening at the bottom and said compartment being provided with an air outlet opening, each of said partitions consisting of a plurality of doors.

3. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating 90 means located in the space between said second partition and the adjacent wall, said space being provided with an air inlet opening at the bottom and said compartment being provided with an air outlet opening, each of said partitions being mounted on 95 hinges, the hinges for the partition nearer the adjacent wall being nearer the bottom of such partition and those for the other partition being near the top of such partition.

4. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from 105 each other and from said wall, heating means located in the space between said second partition and the adjacent wall, said space being provided with an air inlet opening at the bottom and said compartment being provided with an air outlet opening, each of said partitions being mounted on 110 hinges.

5. A dry kiln, consisting of a main or outer compartment having a ceiling and walls, a partition projecting downward into said compartment near one wall, a second partition projecting upward between said first partition and the adjacent wall, said partitions being respectively spaced from 115 the floor and the ceiling of said compartment and the two partitions being spaced from each other and from said wall, heating means located in the space between said second partition and the adjacent wall, said 120 space being provided with an air inlet opening at the bottom and said compartment being provided with an air outlet opening, each of said partitions being mounted on 125 hinges.

130

- ing provided with an air inlet opening at the bottom and said compartment being provided with an air outlet opening.
6. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided with an air inlet opening at the bottom and said compartment being provided with an air outlet opening, and an open water vessel located under the lower edge of said first partition.
7. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided with an air inlet opening at the bottom, an open water vessel located under the lower edge of said first partition, and an air outlet pipe extending from the lower part of said compartment beneath said water vessel and through said second partition.
8. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided with an air inlet opening at the bottom, and an air outlet pipe extending from the lower part of said compartment through said second partition and up through the space in which said heating means is located.
9. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided with an air inlet opening at the bottom, an open water vessel located under the lower edge of said first partition, and an air outlet pipe extending from the lower part of said compartment beneath said water vessel and through said second partition and up through the space in which said heating means is mounted.
10. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided with an air inlet opening at the bottom, and an air outlet pipe extending from the lower part of said compartment through said second partition.
11. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom and said compartment being provided with an air outlet opening.
12. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom and said compartment being provided with an air outlet opening, and an open water vessel located under the lower edge of each of said first-named partitions.
13. A dry kiln, consisting of a main or

- outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and there being two air outlet openings beneath the respective second-named partitions, a damper controlling the air inlet opening to each of said spaces, and a valve controlling each of said air outlet openings.
14. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, an open water vessel located under the lower edge of each of said first-named partitions, and there being two air outlet openings beneath the respective water vessels and second-named partitions, a damper controlling the air inlet opening to each of said spaces, and a valve controlling each of said air outlet openings.
15. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and there being two air outlet openings, a damper controlling the air inlet opening to each of said spaces, and a valve controlling each of said air outlet openings.
16. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and there being two air outlet openings, a damper controlling the air inlet opening to each of said spaces, and a valve controlling each of said air outlet openings.
17. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, two sets of air outlet pipes extending under the respective second-named partitions and up through the spaces between them and the adjacent walls, a damper controlling the air inlet to each of said spaces, and valve means controlling the flow of air through each of said sets of air outlet pipes.
18. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, an open water vessel located under the lower edge of each of said first-named partitions, two sets of air outlet pipes extending under the respective water vessels and second-named partitions and up through the spaces between them and the adjacent walls, a damper controlling the air inlet openings to each of said spaces, and valve means controlling the flow of air through each of said sets of air outlet pipes.
19. A dry kiln, consisting of a main or

- outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and there being two air outlet openings beneath the respective water vessels and second-named partitions, a damper controlling an air inlet opening, and a valve controlling an air outlet opening.

20. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and an air outlet pipe extending under a second-named partition and up through the space between that partition and the adjacent wall.

25. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and an air outlet pipe extending under a second-named partition and up through the space between that partition and the adjacent wall.

30. A dry kiln having a ceiling, walls, and intermediate partitions, forming a main drying chamber and two feeding spaces, said two feeding spaces being on opposite sides of one of the partitions and being interconnected at their upper ends, and one of said feeding spaces being between the other feeding space and the main drying chamber, heating means in one of said feeding spaces, the feeding space in which said heating means is located being provided near its lower end with an air inlet opening and the lower end of the other feeding space being connected to said main drying chamber, humidifying means in the connection between said last-named feeding space and the main drying chamber, and an air outlet pipe leading from the lower part of said main drying chamber upward through the feeding space containing the heating means.

35. A dry kiln having a ceiling, walls, and intermediate partitions, forming a main drying chamber and two feeding spaces, said two feeding spaces being on opposite sides of one of the partitions and being interconnected at their upper ends, and one of said feeding spaces being between the other feeding space and the main drying chamber, heating means in one of said feeding spaces, the feeding space in which said heating means is located being provided near its lower end with an air inlet opening and the lower end of the other feeding space being connected to said main drying chamber, humidifying means in the connection between said last-named feeding space and the main drying chamber, and an air outlet pipe leading from the lower part of said main drying chamber upward through the feeding space containing the heating means.

40. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and an air outlet pipe extending under a second-named partition and up through the space between that partition and the adjacent wall.

45. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and an air outlet pipe extending under a second-named partition and up through the space between that partition and the adjacent wall.

50. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening at the bottom, and an air outlet pipe extending under a second-named partition and up through the space between that partition and the adjacent wall.

55. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said

space being provided at the bottom with air inlet openings both from the atmosphere and from the space on the other side of said second partition, and said compartment being provided with air outlet pipes.

26. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided at the bottom with air inlet openings both from the atmosphere and from the space on the other side of said first partition, and said compartment being provided with air outlet pipes, and an open water vessel located under the lower edge of said first partition.

27. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided at the bottom with air inlet openings both from the atmosphere and from the space on the other side of said second partition, and an air outlet pipe extending from the lower part of said compartment through said second partition and up through the space in which said heating means is located.

28. A dry kiln, consisting of a main or outer compartment having a ceiling and walls, a partition projecting downward into said compartment near one wall, a second partition projecting upward between said first partition and the adjacent wall, said partitions being respectively spaced from the floor and the ceiling of said compartment and the two partitions being spaced from each other and from said wall, heating means located in the space between said second partition and the adjacent wall, said space being provided at the bottom with air inlet openings both from the atmosphere and from the space on the other side of said second partition, and an air outlet pipe extending from the lower part of said compartment through said second partition.

29. A dry kiln, consisting of a main or outer compartment having a ceiling and walls, a partition projecting downward into

said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening from the atmosphere and an air return opening from the central space beyond the associated partitions, and said compartment being provided with an air outlet opening.

30. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, one of said spaces being provided with an air inlet opening from the atmosphere and the other with an air return opening from the central space beyond the associated partitions, and said compartment being provided with an air outlet opening.

31. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening from the atmosphere and an air return opening from the central space beyond the associated partitions, and said compartment being provided with an air outlet opening, and valves controlling the air flow through the several openings.

32. A dry kiln, consisting of a main or outer compartment having a ceiling and walls, a partition projecting downward into said compartment near each of two walls, a partition projecting upward between each of said first partitions and the adjacent wall, said first and second-named partitions being respectively spaced from the floor and the ceiling of said compartment and the two

partitions near each wall being spaced from each other and from said wall, heating means located in the space between each of said second-named partitions and the adjacent wall, one of said spaces being provided with an air inlet opening from the atmosphere and the other with an air return opening from the central space beyond the associated partitions, and an air outlet pipe extending under a second-named partition and up through the space between that partition and the adjacent wall.

33. A dry kiln, consisting of a main or outer compartment having a ceiling and walls, a partition projecting downward into said compartment near each of two walls, a partition projecting upward beyond each of said first partitions and the adjacent wall, said first and second-named partitions being respectively spaced from the floor and the ceiling of said compartment and the two partitions near each wall being spaced from each other and from said wall, heating means located in the space between each of said second-named partitions and the adjacent wall, each of said spaces being provided with an air inlet opening from the atmosphere and an air return opening from the central space beyond the associated partitions and an air outlet pipe extending under a second-named partition and up through the space between that partition and the adjacent wall.

34. A dry kiln having a ceiling, walls, and intermediate partitions, forming a main drying chamber and two feeding spaces, said two feeding spaces being on opposite sides of one of the partitions and being interconnected at their upper ends, and one of said feeding spaces being between the other feed-

ing space and the main drying chamber, heating means in one of said feeding spaces, the feeding space in which said heating means is located being provided near its lower end with an air inlet opening from the atmosphere and a return air opening from the main drying space and the lower end of the other feeding space being connected to said main drying chamber, humidifying means in the connection between said last-named feeding space and the main drying chamber, and an air outlet pipe leading from the lower part of said main drying chamber upward through the feeding space containing the heating means.

35. A dry kiln having a ceiling, walls, and intermediate partitions, forming a main drying chamber and two feeding spaces, said two feeding spaces being on opposite sides of one of the partitions and being interconnected at their upper ends, and one of said feeding spaces being between the other feeding space and the main drying chamber, heating means in one of said feeding spaces, the feeding space in which said heating means is located being provided near its lower end with an air inlet opening from the atmosphere and a return air opening from the main drying space and the lower end of the other feeding space being connected to said main drying chamber, and an air outlet pipe leading from the lower part of said main drying chamber upward through the feeding space containing the heating means.

In witness whereof, I have hereunto set my hand at Indianapolis, Indiana, this ninth day of February, A. D. one thousand nine hundred and seventeen.

HARRY HUNTER.
